THERMOSTAT

Howard W. Bletz, Lexington, Ohio, assignor to Stevens Manufacturing Company, Inc., a corporation of Ohio

Application January 3, 1956, Serial No. 557,120

13 Claims. (Cl. 200—138)

The invention relates in general to thermostats and more particularly to the use of an insulator bushing which is recessed inboard of the flat bearing surfaces near the outer periphery of the bushing so as to obtain an accurately controlled free length of bimetallic element used in the thermostat.

The prior art form of thermostats in many instances incorporated a stack of elements which were mutually separated and insulated by insulator spacers. Where these thermostats are subjected to high temperatures in the electrical device which they control, the insulator must necessarily be able to withstand such temperatures. Mica and porcelain have been two commonly used insulators. The thermostat often comprises one or more flexible strips carrying contacts and a bimetallic strip or element to relatively move the contacts. The strips are assembled in a stack, with apertures in each strip aligned and with the insulator spacers separating and insulating these strips. A hollow rivet is often used to fasten the stack together and to the base of the thermostat.

When porcelain washers or spacers have been used in the past in thermostats, it has been found that the porcelain spacers are not perfectly flat. The porcelain starts out as a damp powder which is pressed into a desired shape and then fired to make it hard and in finished form. This firing quite frequently warps the porcelain insulator, and this is the primary cause of opposing surfaces not being planar nor parallel. The edges of the porcelain insulator may be curved upwardly or downwardly from the desired flat plane, and this curvature lying adjacent either a contact strip or the bimetallic strip can change the active free length of the bimetal or of the contact strips. This change of free length changes the amount of resiliency; and when it occurs in the bimetallic strip, it also changes the movement per degree of temperature change. This affects the temperature differential and affects the temperature range from low to high position in an adjustable thermostat.

Accordingly, an object of the invention is to provide a thermostat wherein the opposite faces of insulator spacers are more nearly planar.

Another object of the invention is to provide an insulator spacer for a thermostat wherein the temperature range between low and high adjustable positions is more nearly constant for successively manufactured thermostats.

Another object of the invention is to provide an insulator spacer for a thermostat which has a recess inboard of an outer bearing surface to definitely establish the outermost surface of the insulator spacer as the bearing surface for contact strips and bimetallic strips in the thermostat.

Another object of the invention is to provide a thermostat construction utilizing insulating spacers wherein the temperature differential between on and off conditions is more nearly uniform between successively manufactured thermostats.

Another object of the invention is to provide a ther-

2

mostat construction wherein the active length of flexible bimetallic element or contact arms is more accurately controlled.

Another object of the invention is to produce a thermostat utilizing porcelain bushings or other frangible insulator bushings or spacers which are clamped in a stack yet wherein the amount of breaking of such frangible bushings during assembly is materially reduced.

Another object of the invention is to provide a particular shape of an insulator bushing made of a fired porcelain which is cast from a damp powder or the like, which shape assures that, as the damp powder pressing the tool or die wears, the porcelain bushings produced will still remain usable.

Other objects and a fuller understanding of this invention may be had by referring to the following description and claims, taken in conjunction with the accompanying drawing, in which:

Figure 1 is a side elevational view partly in section of a thermostat embodying the invention;

Figure 2 is a top view of the thermostat of Figure 1;

Figure 3 is an enlarged plan view of the insulator bushing used in the thermostat;

Figure 4 is a side view of the bushing;

Figure 5 is a longitudinal sectional view of the bushing of Figure 3; and

Figure 6 is an enlarged sectional view of a prior art form of insulator bushing.

The present invention relates to an improved thermostat which incorporates an improved type of insulator bushing 11 as shown in Figures 3, 4, and 5. This insulator bushing may be used in any of a number of thermostats, and Figures 1 and 2 show for purposes of illustration a typical thermostat 12 with which this insulator bushing

35 may be used. The simple form of thermostat 12 shown in Figures 1 and 2 includes a rigid base 13, a stack 14 rigidly fastened to the base 13, an adjusting screw 15, a bimetallic strip 16, and cooperable contacts 17 and 18. The bimetallic strip 16 is typical of any of several constructions in which changes of temperature effect a movement which relatively moves contacts 17 and 18. In this case the two contacts 17 and 18 are shown as carried on contact arms 19 and 20, respectively, with a first end of each containing a circular aperture 21. Terminals 24 and 25 are respectively in contact with the contact arms 19 and 20, and each also has a circular aperture 26 aligned in the stack 14. Two of the insulator bushings 11 are used to mutually separate and insulate the contact arms 19 and 20 and bimetallic strip 16. This bimetallic strip 16 also has an aperture 27 aligned in the stack 14. Another insulator spacer 30 is provided to separate and insulate the upper contact arm 19 and the base 13.

45 A hollow rivet 32 is used as a clamping member for the thermostat to clamp the stack 14 to the base 13. This hollow rivet 32 has an enlarged head 33 adjacent the bimetallic strip 16 and a shank 34 extending through the aligned apertures, and this shank may be considered as that which aligns all the apertures. A formed head 35 formed by pressing or peening is provided adjacent the base 13 to establish axial pressure on the stack 14.

55 A nut 38 is fixedly attached to the base 13 and carries the adjusting screw 15 which has an insulating stem 39 acting on the contact arm 20 for adjustment of the contact 18. This illustrates a typical method of adjustment of the operating temperature of the thermostat and is representative of ways in which the relative spacing between the contacts 17 and 18 may be effected.

60 The particular shape of the insulator bushings 11 is best shown in Figures 3, 4, and 5 and includes generally a washer portion 41 and an axial portion 42. This axial portion extends on only one side of the washer portion 41 and, as shown in Figure 1, it provides radial separation

65 70 a washer portion 41 and an axial portion 42. This axial portion extends on only one side of the washer portion 41 and, as shown in Figure 1, it provides radial separation

between the contact arms 19 and 20 and the shank 34. This axial portion 42 is therefore a centering means to accurately align all apertures, especially the apertures in the contact arms 19 and 20, and to make certain that these contact arms are mutually insulated as well as electrically insulated from the shank 34 and the rest of the thermostat 12.

The washer portion 41 has a circular periphery 44 and adjacent this periphery are first and second bearing surfaces 45 and 46. These bearing surfaces are annular or washer-shaped and lie in substantially parallel planes. Just inboard of the first bearing surface 45 is a first recess 47 which is disposed between such first bearing surface and the axial portion 42. A second recess 48 is generally axially opposite the first recess 47 but extends completely across the axial portion 42. The depth of these recesses is not great and is preferably in the order of one-fourth the radial width of the first recess 47.

The first recess 47 is formed by first and second recessed shoulders 49 and 50 with the first of these being the most important. These shoulders are formed by corners which are relatively sharp but, of course, all such corners are in actual practice rounded to some degree. The fact that this first recessed shoulder 49 is a relatively sharp corner makes certain that the outer cylindrical surface 51 of the axial portion 42 extends below the plane of the first bearing surface 45 before the fillet or rounded corner begins. This is important because the aperture 21 of the contact arm 19 or 20 lies closely adjacent this outer cylindrical surface 51, and it is highly desirable that such contact arm or other contiguous operating element of the thermostat 12 lie against the bearing surface 45 rather than on any such rounded corner.

The insulator bushings 11 are preferably made from a fired porcelain which initially exists as a damp powder or the like and is pressed or molded into shape by a pressing or forming tool or die. Such pressing tool must necessarily have a sharp outer corner to form the first recessed shoulder 49. As this pressing tool wears, this outer corner will become less sharp and thus create a continually greater and greater radius fillet at the first recessed shoulder 49 in the final porcelain bushing 11. Thus, by initially providing the recesses 47 and 48, the porcelain bushings 11 are usable even after the porcelain pressing tool wears considerably.

After the damp powder is pressed into shape, it is fired and during this firing which makes the porcelain into the hard finished product, warping and twisting inevitably occurs. The Figure 6 shows a prior art form of porcelain bushing 54 which did not contain any recesses on the washer portion 55. The broken lines 56 show that the edges of the washer portion 55 may warp downward slightly during firing or the broken lines 57 indicate that this porcelain bushing may warp upwardly to a greater or less extent during firing. It will be noted from Figure 1, the distance from the center line 59 to the edge of the porcelain bushing is not great compared to the free length of the bimetallic strip 16 or contact arms 19 and 20. Thus, if the washer portion 55 should warp upwardly as shown by the broken line 57, then it would not be nearly as definite a fulcrum or abutment about which the flexible element will bend. This means that the active length of bimetal is variable between successively manufactured thermostats, and thus the temperature differential between on and off conditions of the contacts 17 and 18 will vary widely and also the temperature range between high and low adjustment position of the adjustment screw 15 will also have wide variations.

The insulator bushing 11 of the present invention shown in Figures 3, 4, and 5 materially reduces such variations in active length of thermostat elements, it materially reduces the temperature differential of the thermostat, and it materially reduces the temperature range between the high and low adjustment positions. This variation in temperature differential and temperature range between

high and low positions is quite pronounced in the snap-acting type of thermostats, such as is shown in Patent No. 2,692,317 issued October 19, 1954, to Edward Bletz. When the improved form of insulator bushing 11 is used in such snap-acting type of thermostat, the performance of such thermostat is considerably improved to make more uniform successively manufactured thermostats.

During assembly of the thermostat 12, or any such thermostat utilizing a stack of a plurality of elements, the hollow rivet 32 is placed through the aligned apertures and then spun, peened, or pressed over to form the formed head 35. During such operation an axial force is applied to the stack 14 so as to tightly assemble all elements in the stack. Past experience has shown that for a particular force applied to the stack breakage of one or more of the insulator bushings or spacers 11 and 30 was approximately 5 percent, with the old prior art form of insulators. Utilizing the same thermostat construction and the same axial force during rivet head forming operations, the breakage of insulators has been reduced to about 1 to 2 percent; and therefore, this is about a 200 percent increase in manufacturing efficiency on this one operation alone to thus reduce scrap losses. The reason for the reduced breakage of insulators is believed to be that the bearing surfaces 45 and 46, being shorter in radial extent, have less total warpage away from the desired flat planar condition; and therefore, localized positions of high unit stress on the porcelain bushings are avoided. Because there is less total warpage, there is a more constant active length of bimetallic strip or contact arms to give more uniform thermostat operating conditions including temperature differential and temperature range. Also, the warpage, whatever there is of it during the firing of the porcelain, is confined to areas of the bushings which are closer to the outer periphery than in the prior art form. For example, under the extreme and exaggerated condition of upward warping, as shown in Figure 6, the fulcrum for the bimetallic element would be at point 60 rather than at point 61; and this would greatly affect the active length of bimetallic strip. However, in the approved form of thermostat, if the porcelain bushing should warp upwardly to a very great extent, the fulcrum point would be at point 62 rather than at point 63 and this would not change the operating conditions of the thermostat nearly as much as if the fulcrum were at point 64 which corresponds to the point 60 on the prior art form of bushing.

The recesses 47 and 48 being inboard of the bearing surfaces 45 and 46 establish that the axial pressure on the stack 14 will be borne at the bearing surfaces 45 and 46 which is near the outer periphery of the insulator bushings or spacers to thus establish that the active free length of bimetallic strip will always begin adjacent the outer periphery of such insulator bushings.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A thermostat comprising, a base, a bimetallic element, an insulator spacer mutually insulating said base and bimetallic element, clamping means acting on said base, element and spacer to clamp same together in a stack, a first circular bearing surface adjacent the outer periphery of said spacer, a first recess on one side of said spacer inboard of said bearing surface, a second circular bearing surface generally axially opposite said first bearing surface to also lie adjacent to the outer periphery of said spacer, a second recess on the opposite side of said bushing of substantially equal diameter as the first recess, 70 and said first and second bearing surfaces lying in sub-

stantially parallel planes, whereby said clamping means exerts an axial pressure on said stack which is borne by said first and second bearing surfaces rather than at the recesses of said spacer to thereby establish a definite free length of bimetallic element.

2. A thermostat comprising, a base having an aperture, a bimetallic element having an aperture, an insulator bushing mutually insulating said base and bimetallic element, a clamping member having a shank passing through said apertures and bushing to place them in substantial alignment and to create a stack and clamping said bimetallic element to said base, a washer portion on said bushing, an elongated axial portion on said bushing extending on only one side of said washer portion, a first annular bearing surface adjacent the outer periphery of said bushing, a first recess on one side of said bushing between said axial portion and said first bearing surface, a second annular bearing surface generally axially opposite said first bearing surface to also lie adjacent to the outer periphery of said bushing, and a second recess on the opposite side of said bushing of substantially equal diameter as the first recess and extending across said axial portion, whereby said clamping member exerts an axial pressure on said stack which is borne by said first and second bearing surfaces rather than at the recesses of said bushing to thereby establish a definite free length of bimetallic element.

3. An insulator spacer for a thermostat comprising, a first circular bearing surface adjacent the outer periphery of said spacer, a first recess on one side of said spacer, inboard of said bearing surface, a second circular bearing surface generally axially opposite said first bearing surface to also lie adjacent to the outer periphery of said spacer, a second recess on the opposite side of said bushing of substantially equal diameter as the first recess, and said first and second bearing surfaces lying in substantially parallel planes.

4. An insulator bushing for spacing a flexible bimetallic element in a thermostat, comprising, a washer portion on said bushing, a first annular bearing surface adjacent the outer periphery of said washer portion, a first recess on one side of said bushing inboard of said first bearing surface, a second annular bearing surface generally axially opposite said first bearing surface to also lie adjacent to the outer periphery of said washer portion, and a second recess on the opposite side of said bushing of substantially equal diameter as the first recess.

5. An insulator bushing for spacing and insulating flexible members in a thermostat, comprising, a washer portion on said bushing, an elongated axial portion on said bushing extending on only one side of said washer portion, a first substantially annular bearing surface adjacent the outer periphery of said bushing, a first recess on one side of said bushing between said axial portion and said first bearing surface, the depth of said first recess being approximately one-fourth the width thereof between said first bearing surface and said axial portion, a second substantially annular bearing surface generally axially opposite said first bearing surface to also lie adjacent to the outer periphery of said bushing, and a second recess on the opposite side of said bushing extending across said axial portion.

6. An insulator bushing for spacing and insulating flexible members in a thermostat, comprising, a washer portion on said bushing, an elongated axial portion on said bushing extending on only one side of said washer portion, a first substantially circular bearing surface adjacent the outer periphery of said bushing, a first substantially coaxial recess on one side of said bushing between said axial portion and said first bearing surface, the depth of said first recess being approximately one-fourth the width thereof between said first bearing surface and said axial portion, a second annular bearing surface generally axially opposite said first bearing surface to also lie adjacent to the outer periphery of said bushing, a second substantially coaxial recess on the opposite side of said bushing

of substantially equal diameter and depth as the first recess and extending across said axial portion, and said first and second bearing surfaces lying in substantially parallel planes.

- 5 7. A thermostat comprising, a base having an aperture, a contact arm and an elongated bimetallic strip each having an aperture at one end thereof, an electrical terminal touching said contact arm and having an aperture substantially coinciding therewith, at least one insulator bushing mutually insulating said contact arm and bimetallic strip, a hollow rivet having a head and having a hollow shank passing through said apertures and bushing to place them in substantial alignment and to create a stack, a formed head on said hollow rivet acting as a clamping member to clamp said bushing, arm, terminal and strip together in said stack, a washer portion on said bushing, an elongated axial portion on said bushing extending on only the adjacent contact arm side of said washer portion, a first annular bearing surface adjacent the outer periphery of said bushing, a first recess on one side of said bushing between said axial portion and said first bearing surface, the depth of said first recess being approximately one-fourth the width thereof between said first bearing surface and said axial portion, a second annular bearing surface generally axially opposite said first bearing surface to also lie adjacent to the outer periphery of said bushing, and a second recess on the opposite side of said bushing of substantially equal diameter as the first recess and extending across said axial portion, whereby said hollow rivet by the two heads thereof exerts an axial pressure on said stack which is borne by said first and second bearing surfaces rather than at the recesses of said bushing to thereby establish a definite free length of bimetallic strip and contact arm.
- 35 8. A thermostat comprising, a base, a plurality of contact arms and a bimetallic strip each fastened together at one end thereof in a stack, apertures in said arms and strip in alignment in said stack, a hollow rivet having a head and passing through said aligned apertures, fired porcelain bushings in said stack mutually separating said contact arms and bimetallic strip from said hollow rivet, a peened head on said hollow rivet adjacent said base acting as a clamping member to clamp said bushings, arms, and strip together in said stack, electrical terminals in said stack adjacent each of said contact arms, a washer portion on each of said bushings, an elongated axial portion on each of said bushings adjacent said contact arms and extending on one side of said washer portion, a first annular bearing surface contiguous with the outer extremity of said bushing, a first substantially coaxial recess on one side of said bushing between said axial portion and said first annular bearing surface, the depth of said first recess being approximately one-fourth the width thereof between said first bearing surface and said axial portion, a second annular bearing surface generally axially opposite said first bearing surface to also lie contiguous to the outer periphery of said bushing, and a second substantially coaxial recess recessed from said second bearing surface on the opposite side of said bushing of substantially equal diameter and depth as the first recess and extending across said axial portion, said first and second bearing surfaces being substantially parallel and perpendicular to the axis of said rivet, whereby said hollow rivet by the peened head thereof exerts an axial pressure on said stack which is borne by said first and second bearing surfaces rather than at the recesses of said bushings to thereby establish a definite free length of bimetallic strip and contact arms.
- 70 9. A thermostat comprising, a base having a circular aperture, a plurality of elongated flexible contact arms and an elongated bimetallic strip each having a circular aperture at one end thereof, an electrical terminal touching each of said contact arms and each having an aperture substantially coinciding with that of the contiguous

contact arm, fired porcelain bushings mutually insulating and separating said contact arms and bimetallic strip, a hollow rivet having a head adjacent said bimetallic strip and having a hollow shank passing through said apertures and bushings to place them in substantial alignment and to create a stack, a formed head on said hollow rivet adjacent said base on the opposite side from said stack acting as a clamping member to clamp said bushings, arms, terminals and strip together in said stack, a washer portion on each of said bushings, an elongated axial portion on each of said bushings extending on only the adjacent contact arm side of said washer portion, a first annular bearing surface contiguous to the outer periphery of said bushing, a first substantially coaxial recess on one side of said bushing between said axial portion and said first bearing surface, the depth of said first recess being approximately one-fourth the width thereof between said first bearing surface and said axial portion, a second annular bearing surface generally axially opposite said first bearing surface to also lie contiguous to the outer periphery of said bushing, a second substantially coaxial recess on the opposite side of said bushing of substantially equal diameter and depth as the first recess and extending across said axial portion, and said first and second bearing surfaces lying in substantially parallel planes, whereby said hollow rivet by the two heads thereof exerts an axial pressure on said stack which is borne by said first and second bearing surfaces rather than at the recesses of said bushings to thereby establish a definite free length of bimetallic strip and contact arms.

10. An insulator spacer for a thermostat comprising, a first bearing surface adjacent at least part of the outer periphery of said spacer, a recess on one side of said spacer inboard of said bearing surface, a second bearing surface generally axially opposite said first bearing surface to also lie adjacent part of the outer periphery of said spacer, and said first and second bearing surfaces lying in substantially parallel planes.

11. An insulator spacer for a thermostat comprising, a first bearing surface adjacent at least part of the outer periphery of said spacer, a first recess on one side of said spacer inboard of said bearing surface, a second bearing surface generally axially opposite said first bearing surface to also lie adjacent to part of the outer periphery of said spacer, a second recess on the opposite side of said bushing of substantially the same size as the first

recess, and said first and second bearing surfaces lying in substantially parallel planes.

12. A thermostat comprising, a base, a bimetallic element, an insulator spacer mutually insulating said base and bimetallic element, clamping means acting on said base, element and spacer to clamp same together in a stack, a first bearing surface adjacent at least a part of the outer periphery of said spacer, a first recess on one side of said spacer inboard of said first bearing surface, a second bearing surface generally axially opposite said first bearing surface to also lie adjacent to part of the outer periphery of said spacer, and a second recess on the opposite side of said bushing of substantially the same size as the first recess, whereby said clamping member exerts an axial pressure on said stack which is borne by said first and second bearing surfaces rather than at the recesses of said spacer to thereby establish a definite free length of bimetallic element.
13. A thermostat comprising, a base having an aperture, a bimetallic element having an aperture, an insulator bushing mutually insulating said base and bimetallic element, a clamping member having a shank passing through said apertures and bushing to place them in substantial alignment and to create a stack and clamping said bimetallic element to said base, a washer portion on said bushing, an elongated axial portion on said bushing extending on only one side of said washer portion, a first bearing surface adjacent at least part of the outer periphery of said bushing, a first recess on one side of said bushing between said axial portion and said first bearing surface, a second annular bearing surface generally axially opposite said first bearing surface to also lie adjacent to a part of the outer periphery of said bushing, and a second recess on the opposite side of said bushing of substantially the same size as the first recess, whereby said clamping member exerts an axial pressure on said stack which is borne by said first and second bearing surfaces rather than at the recesses of said bushing to thereby establish a definite free length of bimetallic element.
